Primary Examiner — Susan Bennett Hattan*Assistant Examiner* — Brett Miller(74) *Attorney, Agent, or Firm* — Duane Morris LLP(57) **CLAIM**

We claim the ornamental design for a packaging for food product, as shown and described.

DESCRIPTION

FIG. 1 is a perspective view of the claimed design;
FIG. 2 is a top view thereof;
FIG. 3 is a bottom view thereof;
FIG. 4 is a front view thereof;
FIG. 5 is a right side view thereof;
FIG. 6 is a left side view thereof;
FIG. 7 is a rear view thereof; and,
FIG. 8 is a section view thereof taken along line 8-8 in FIG. 4. The dash-dash and dash-dot boundary lines(s) defines the boundary of the claimed design and forms no part of the claimed design. The design is shown with symbolic break lines. The appearance of any portion of the article between the break lines forms no part of the claimed design. The broken lines depict portions of the packaging for food product that form no part of the claimed design.

1 Claim, 8 Drawing Sheets
